UNITED STATES PATENT OFFICE

GOTTLIEB LIEBENDER, OF OLSNITZ, GERMANY, ASSIGNOR TO KOCK AND TE KOCK, OF OLSNITZ, GERMANY, A FIRM

DEVICE FOR LOOMS EMPLOYED IN WEAVING PREPARATORY CHENILLE MATERIAL FOR THE MANUFACTURE OF AXMINSTER CARPETS AND THE LIKE

Original application filed May 3, 1928, Serial No. 274,781. Divided and this application filed May 30, 1930, Serial No. 457,642, and in Germany March 18, 1927.

This invention is related to my Patent No. 1,783,125, dated November 25, 1930.

This invention relates to a weft selecting device for looms employed in weaving preparatory chenille material for the manufacture of Axminster carpets and of the kind wherein differently coloured weft threads are fed to a pair of grippers through pivotally deflected tubes which are selected by a 5 Jacquard mechanism, and the invention consists in the provision of a stop which maintains the selected tube in operative position and which is released through the medium of a lever for a change of tube after a pre-determined number of picks.

Fig. 1 of the accompanying drawings represents a front view of the weft selecting device,

Fig. 2 is a side view of a modification of 20 the same, and

Fig. 3 is a side view of a device for timing the release of the stop.

The differently coloured weft threads are fed through guide tubes 28 which are controlled by springs 48 and pivoted by means of holders to brackets 29 arranged radially beneath an arcuate carrier so that any arm can be brought with its mouth-piece 64 into the path of a pair of reciprocating grippers 30 51 whereby the thread 69 is extracted from the tube outside the heddles 56 and 57, as shown in Fig. 2.

The tubes are selected through the medium of a Jacquard mechanism which is of any 35 ordinary form but which it is not deemed necessary here to show which acts on vertical rods 32 connected to lever arms 30 on the tube holders. The rods 32 are guided in slots 33 and 34 in the machine frame, and 40 each rod carries a nose-piece 35 which, on the respective tube being turned into operative position, passes and then engages a stop rod 36, the latter being common to all the tubes. The stop rod, which maintains the 45 tube in operative position, is carried by arms connected to a rock shaft, and an additional arm on the latter engages a double-armed release lever 37 resting against a stop pin 39. The release lever 37 may be operated, 50 through the medium of the Jacquard mecha-

nism, by means of a spring-controlled pull 38 for releasing the stop rod 36 and effecting a change of weft thread whenever required.

Fig. 2 shows a device whereby the release of a stop and the change of weft may be effected by means of the Jacquard cards and whereby the number of successive picks of the same thread can be varied automatically. The release lever 37 is adapted to co-operate with tappets 41 connected to a series of 55 discs 40 mounted on bell cranks 61 arranged to rock about a shaft 44. Bell-cranks and discs normally occupy the position shown by dotted lines in Fig. 2, and they are moved selectively through the medium of the Jacquard cards into the operative position shown by full lines. Each disc is connected to a ratchet wheel 42 which in the operative position engages the detent pawl 47 and also engages with an operating pawl 60 (not shown) mounted on a reciprocating slide 43. The discs are controlled by springs 45 and their normal angular positions are determined by stops 60 which abut against the arms of the bell cranks 61. The tappets 41 65 of the individual discs are situated at different distances from the stops 60, and the number of beats required for bringing the tappets into contact with the release lever and effecting a change of weft, will therefore 70 be different for each particular disc. On the discs being withdrawn from the pawl they are restored by the springs 45 to their normal 75 positions.

Having now particularly described and ascertained the nature of my said invention and in what manner the same is to be performed, I declare that what I claim is:—

1. In a device of the kind described, a series of tiltably mounted weft tubes, Jacquard rods 90 connected to said tubes to tilt the same into and out of weft delivering positions selectively, a nose piece on each of said rods, and a stop rod extending transversely of the Jacquard rods in the paths of said nose pieces 95 and constituting a latch to hold the respective tubes tilted.

2. In a device of the kind described, a series of tiltably mounted weft tubes, Jacquard rods connected to said tubes to tilt the 100

same into and out of weft delivering positions selectively, a nose piece on each of said rods, a stop rod extending transversely of the Jacquard rods in the paths of said nose pieces and constituting a latch to hold the respective tubes tilted, an arm on which said stop rod is supported, a pivot for said arm, a trip arm projecting from the first arm, a trip lever pivoted to rest against the trip arm and movable to move the stop rod into nose releasing position.

3. In a device of the kind described, a series of tiltably mounted weft tubes, Jacquard rods connected to said tubes to tilt the same into and out of weft delivering positions selectively, a nose piece on each of said rods, a stop rod extending transversely of the Jacquard rods in the paths of said nose pieces and constituting a latch to hold the respective tubes tilted, an arm on which said stop rod is supported, a pivot for said arm, a trip arm projecting from the first arm, a trip lever pivoted to rest against the trip arm and movable to move the stop rod into nose releasing position, and means for automatically varying the number of successive picks of the same thread.

4. In a device of the kind described, a series of tiltably mounted weft tubes, Jacquard rods connected to said tubes to tilt the same into and out of weft delivering positions selectively, a nose piece on each of said rods, a stop rod extending transversely of the Jacquard rods in the paths of said nose pieces and constituting a latch to hold the respective tubes tilted, an arm on which said stop rod is supported, a pivot for said arm, a trip arm projecting from the first arm, a trip lever pivoted to rest against the trip arm and movable to move the stop rod into nose releasing position, means for automatically varying the number of successive picks on the same thread, said means comprising a series of disks, a series of tappets connected to the disks, the said disks being selectable by the Jacquard cards and operated by the loom, the said tappets being arranged on the disks in order that the number of loom beats required for the release lever is different for each particular disk.

Dated the 12th day of May, 1930.

GOTTLIEB LIEBENDER.
